UNITED STATES PATENT OFFICE.

LOUIS STEINBERGER, OF BROOKLYN, NEW YORK.

INSULATOR.

Application filed March 15, 1917. Serial No. 154,914.

To all whom it may concern:

Be it known that I, LOUIS STEINBERGER, a citizen of the United States, and a resident of the borough of Brooklyn, county of 5 Kings, city and State of New York, have invented certain new and useful Improvements in Insulators, of which the following is a specification.

This invention relates to improvements in 10 insulating devices, commonly known as "pin insulators" and the particular type to which the invention relates is that which may be secured rigidly at one end to a suitable support and is capable not only of withstanding 15 mechanical strains, but high potentials.

One of the objects of my invention is to provide a pin insulator which is simple and efficient in construction, the parts of which are easily assembled.

20 Another object is to provide means for securely holding the insulating material to its supporting base in such a position as to minimize the danger of deterioration due to the effects of dielectric stress on the insula- 25 tor.

Another object is to locate the locking means between the supporting pin and the insulating material at a maximum distance from the line.

30 Another object is to provide a metal lined cavity in an insulator within which the supporting pin is secured.

Other objects will appear from the following description and claims.

35 Referring to the drawings:

Fig. 1 is a vertical section through my improved compound insulator and support.

Fig. 2 is a front elevation of the centre pin to which the insulator is secured.

40 Fig. 3 is a front elevation of a modified form of pin shown broken away at the lower portion thereof.

Fig. 4 is a section in line 4—4 of Fig. 2.

In the drawings like reference characters 45 refer to like parts.

A is a cross arm or support to which the supporting pin is attached, B is the supporting pin and C is the lower and D the upper section of the insulator. The lower 50 portion 10 of the supporting pin extends through and closely fits the opening 11 in the cross arm A, the extreme lower end of the pin being preferably screw-threaded at 13 to engage with lock nuts 14. Extending radially from the pin and longitudinally thereof are a plurality of fin shaped projections

15, so shaped that their under-sides at 16 will rest securely upon a plate 16' on the cross arm A. Screw-threads 17 are provided on the pin immediately above the upper ends 60 of the projecting fins 15 and these threads extend along the pin for a suitable distance to accomplish the purpose for which they are designed which will be hereinafter described. The pin which is substantially 65 conical in shape extends upwardly a suitable distance, the top of which is provided either with a convex surface, as shown in Fig. 2, or a flat surface as shown in Fig. 3. A suitably formed metal lining 20 is provided for 70 the cavity in the insulator C so as to fit the same closely throughout the length of the cavity to the base of the screw-threaded portion, the lower end of the metal lining at 21 having screw-threads 30 formed therein to 75 engage the screw-threads 17 on the pin. This lining may be formed in any suitable way, but it is preferably constructed of sheet material.

The insulating portion of my device which 80 is preferably in two parts, one secured to the other, may be made of any approved insulating material, but I prefer to use in this construction a material known in the art as "Electrose." Projecting radially from the 85 body of the lower portion of the insulator are a series of circumferential sheds or hoods 25, the diameter of the respective hoods progressively decreasing from top to bottom. This portion of the insulator has 90 formed therein a central longitudinal bore or cavity 26 open at its lower end at 27 and closed at its inner end at 28 and so shaped that the pin and the metal lining will completely fill the same. Extending inwardly 95 from the lower end of the cavity for a short distance only are a series of screw-threads 29 which closely fit and engage the screw-threads 30 of the metal lining and by means of which the pin and insulator are removable held together.

As indicated in the drawings, it is my purpose to provide screwthreads at the base of the bore of the insulator to extend only a sufficient distance to securely hold the insulator in place and at a point which is remote from the point of contact of the line wire with the insulator. The remaining portion of the walls of the bore is smooth and the bore and pin are so shaped that a close 110 and snug fitting will be made between them.

My purpose in providing a screwthread of

minimum extent or surface is to lessen the number of ridges or protrusions which when present tend to cause the insulator to puncture at those points owing to the concentration of electro-static stresses due to the position of the surface of the screwthreads. The smooth surfaces of the bore and pin which extend throughout the greater portion of the same greatly reduces this danger.

10 The upper end of the lower section of insulating material is convex at 31 and is provided with screw-threads 32 at the base of the convex portions to which is fitted the other section of the insulator which is provided with a cavity 33 complementary in shape to the convex and screw-threaded end of the lower section. The upper section D is held in place to the lower section C by means of the screw-threads above described.

15 20 The upper section of insulator is provided with a shed or hood 34 extending radially and circumferentially therefrom and having a diameter slightly greater than the diameter of the shed or hood 25 next below.

25 30 The under side of the shed or hood 34 is provided with a waved under surface in order to more effectually lengthen the insulating path. A groove 35 is arranged at the top of section D of insulating material extending diametrically along the same for the reception of the line wire, and a circumferential groove 36 is also provided just above its shed or hood 34 for the reception of a securing wire.

35 40 45 While I have preferably employed a metallic lining for the cavity for the supporting pin throughout the surface thereof which engages the insulating material, this metal lining may be dispensed with and the pin fitted directly to the bore or cavity in the insulator by means of the screw-threads as above described. The pin is preferably made of wood or may obviously be constructed of any other suitable material and may even be formed entirely of metal.

It is to be understood that the above description and drawings are merely illustrative and the invention is not to be limited

in any respect except as defined in the subjoined claims.

Having described my invention, what I claim as new and desire to secure by Letters Patent, is:

1. An insulator and supporting pin therefor, said insulator having a bore extending thereinto from the lower side or end thereof, the pin fitting and extending into said bore, said bore and pin having their adjacent surfaces smooth and free from protuberances or projections throughout the upper and greater portion of their extent, mutually engaging securing means between the insulator and the supporting pin, said securing means located only at the lower end or side of the insulator and remote from the apex of the pin, and a seat for the line wire on the upper end or side of the insulator remote from said securing means.

2. In an insulator, a body of insulating material provided with a line wire seat at one end and a conically shaped bore through the central portion thereof closed at one end and open at the other, a metal lining for said bore secured thereto only at the base of the insulating body, and a supporting pin secured by screw threads to said metal lined bore at the same point only.

3. A pin insulator provided with a pin securing bore, a metal lining for said bore and means for removably securing the lining to the bore at its base only.

4. An insulator body provided with means for securing the line wire at one end and having a conical bore in the central portion thereof, the wall of the bore being smooth throughout the greater portion of its length and provided with screw threads at its base only.

In witness whereof I have hereunto set my hand at borough of Manhattan, county of New York, and State of New York, this 12th day of March, 1917.

LOUIS STEINBERGER.

In presence of—

ZITA M. GRAHAM,
ISABEL R. RICHARDS.
